JOSEPH GERDOM, JR., OF WEST ALBANY, NEW YORK.

Letters Patent No. 68,973, dated September 17, 1867.

IMPROVED CHAIR, LOUNGE, AND STEP-LADDER.

The Schedule referred to in these Letters Patent and making part of the same.

TO ALL WHOM IT MAY CONCERN:

Be it known that I, JOSEPH GERDOM, Jr., of West Albany, in the county of Albany, and State of New York, have invented a new and combined Chair, Lounge, and Step-Ladder; and I do hereby declare that the following is a full, clear, and exact description thereof, which will enable those skilled in the art to make and use the same, reference being had to the accompanying drawings, forming part of this specification, in which—

Figure 1 represents a side elevation of my improved step-ladder.

Figure 2 is a longitudinal sectional elevation of my improved chair.

Figure 3 is a longitudinal sectional elevation of my improved lounge or bed.

Figure 4 is a bottom plan view of the latter.

Similar letters of reference indicate corresponding parts.

This invention relates to a new and useful device which will be of great use in stores and magazines of all descriptions, and which is so arranged that it can be set up as a chair, step-ladder, or lounge, as may be desired.

The invention consists in connecting by means of hinges two frames, of which one is a complete chair, without front legs. The front edge of the seat is hinged to the other frame, which is a portion of a step-ladder having a cushioned front; and the under side of the chair frame has also steps which lie close upon the steps of the front frame. When the front frame is folded, so that its cushioned board is horizontal, the latter will form a continuation of the seat of the chair, and a bed or lounge is thus formed. When from the chair-position the chair is folded over the front frame so that it will be turned bottom up, and stand on its head-rest, the steps on the chair will be brought so as to form a continuation of the steps on the front frame, and a step-ladder is thus provided. Suitable hooks or braces are provided to unite the two portions in any one of the three positions.

A represents a chair, having a seat, *a*, head-rest *b*, rear legs *c*, and arm-supports *d*; the latter can be omitted if desired. The front edge of the seat *A* and the lower ends of the legs *c* are connected by three, more or less, steps *e e*, which are secured to the under side of the seat, or to the frame upon which the latter rests, by means of upright bars or supports *f f*, as is clearly shown in fig. 2. The front edge of the seat *a* is connected by means of hinges *g* to a frame or ladder, *B*, which consists of front supports *h h*, three, more or less, steps *i i*, and supports or frames *j j*, for the latter. The chair *A* rests upon the ladder *B* in such a manner that the steps *e e* rest upon the steps *i i*; as is clearly shown in fig. 2. *k* is a hook, by which the legs *c* or a brace which connects the same, are connected with and secured to the outer edge of the lower step *i*, as shown, whereby the stability of the chair is insured. This chair, which is completely shown in fig. 2, can be used in all stores, counting-houses, and all places of business, as well as in private dwellings, in libraries, &c. The space between the front legs *h* of the chair is cushioned, or otherwise arranged; so that it will correspond with the seat of the chair, which may be formed of rattan, or of springs, moss, or hair, as may be desired. When the frame *B* is turned around its pivots *g*, in the direction of the arrow 1 in fig. 2, it will be brought into such a position that the device rests partly upon the edge of the lower step *i* and upon the lower step *e*, as shown in fig. 3. The cushioned or soft connection between the legs *h* will be on or almost on the same level with the seat *a* of the chair, as shown, and the device can be used as a bed or lounge. *l l* are braces, by which the frames *A* and *B* are secured in the position shown in fig. 3. An extension-plate, *h'*, may be hinged to the lower end of the legs *h*, which, when the lounge is set up, can be folded out, as shown by red lines in figs. 3 and 4. This extension may be provided with legs *h''*, that can be folded together with it when not used, as shown in fig. 1. When the chair is again supposed to be set up, and the upper frame *A* is turned on its pivot *g* in the direction of the arrow 2 in fig. 2, the upper ends of the head-rest *b* come upon the ground and form a support for the frame *A*, which is then turned bottom up; the steps on the frame *A* will be arranged so as to form a continuation of the steps *i*, on the frame *B*, whereby a regular step-ladder, as shown in fig. 1, is arranged. The cushions which formed the seats on the chair and lounge are then held on the inside of the stairs, as is clearly shown in the drawing.

I claim as new, and desire to secure by Letters Patent—

In the chair and step-ladder, combined as described, I claim the arrangement of the additional piece *h'* with its leg *h''*, forming a lounge, and the fastening-wires *l l*, substantially as described for the purpose specified.

The above specification of my invention signed by me this 18th day of May, 1867.
